ATTORNEY.

UNITED STATES PATENT OFFICE.

WILLIAM C. RASTETTER, OF FORT WAYNE, INDIANA.

ADJUSTING DEVICE FOR STRIKING-BAGS.

SPECIFICATION forming part of Letters Patent No. 694,664, dated March 4, 1902.

Application filed October 9, 1901. Serial No. 78,067. (No model.)

To all whom it may concern:

Be it known that I, WILLIAM C. RASTETTER, a citizen of the United States, residing at Fort Wayne, in the county of Allen and State of Indiana, have invented certain new and useful Improvements in Adjusting Devices for Striking-Bags; and I do declare the following to be a full, clear, and exact description of the invention, such as will enable others skilled in the art to which it appertains to make and use the same, reference being had to the accompanying drawing, and to the figures of reference marked thereon, which forms a part of this specification.

15 My invention relates to improvements in adjusting devices for striking-bags; and the object of my improvement is to afford means for vertically adjusting the position of the bag relative to the contact-ring beneath which 20 the bag depends without causing the bag to overreach said contact-ring when the bag is swung in any of its adjusted positions.

I accomplish my object by the construction illustrated in the accompanying drawing, in 25 which—

1 is the contact-ring, and 2 is a bracket supporting the ring. A boss 3 on the bracket 2 ranges above the ring 1 in line with its center. A tube 5 is mounted vertically in said 30 boss and in the axial center of said ring and is vertically adjustable. A set-screw 4 in the side of the boss serves to hold said tube in its adjusted position.

The striking-bag 8 is attached to the lower 35 end of the cord 7, which passes upward entirely through the tube 5 and is secured to the bracket 2 at a point beneath the upper end of said tube. Thus when the tube 5 is raised or lowered the cord 7 moves up or down relative to the tube and the distance between the

bag 8 and the lower end of the tube 5 is varied accordingly. When the cord 7 is adjusted properly, that portion of said cord extending beneath the lower end of the tube 5 is of such length as to allow the bag 8 to swing and 45 strike the ring 1 squarely, and when it is desired to elevate or lower the position of the bag after the cord has been once adjusted it is only necessary to adjust the tube 5 to effect any elevation of the bag within its scope of 50 adjustment, for the cord is taken up or let out (by the vertical movement of the tube) the proper amount to afford the bag the corresponding less or greater swing. To prevent the cord 7 from becoming worn by the ends 55 of the tube 5, I have secured rounded collars 66 upon the ends of said tube, which afford an easy bearing for the cord.

Having described my invention, what I claim as new, and desire to secure by Letters 60 Patent, is—

1. An adjusting device for striking-bags, comprising a contact-ring supported by a bracket; a vertically-adjustable tube arranged at the axial center of said ring; and a cord 65 attached to the bag, passing upward through said tube and secured to said bracket at a point beneath the top of said tube.

2. An adjusting device for striking-bags, comprising the vertically-adjustable tube arranged at the axial center of the contact-ring, and a cord attached to the bag and passing upward through said tube. 70

In testimony whereof I affix my signature in presence of two witnesses.

WILLIAM C. RASTETTER.
